WALL PAPER.

No. 15,174.

Patented July 29, 1884.

UNITED STATES PATENT OFFICE.

ALBERT LEISEL, OF NEW YORK, N. Y.

DESIGN FOR WALL-PAPER.

SPECIFICATION forming part of Design No. 15,174, dated July 29, 1884.

Application filed April 11, 1884. Term of patent 3½ years.

To all whom it may concern:

Be it known that I, ALBERT LEISEL, a citizen of the Empire of Germany, residing in the city of New York, county and State of New York, have invented and produced a new and original Design for Wall or Ceiling Covering, which is especially intended as a panel, of which the following is a specification.

The drawing represents a front plan view of the design.

This design consists of four panels, which may be used singly or in combination for various kinds of decoration. Panel No. 1 consists of a bird standing on a branch of a nut-tree with a spray of leaves and filberts. The lower part of the design shows water, on the surface of which float water-lilies and leaves, also long grass. On the horizon is seen a setting sun with radiating beams of light. Across the landscape a butterfly wings its flight. The groundwork of the design is filled in with a finely-granulated surface. Panel No. 2 consists of a wooded branch of a wild-rose tree, displaying an open bloom and a profusion of leaves. The ground of the design is filled in with a beaded surface. Panels Nos. 3 and 4 are similar to the preceding, with, however, the important distinction that in the first instance the direction of the designs is from left to right, whereas in the second series the direction is from right to left. Each of the squares is surrounded by a border.

I claim—

The design herein described and shown, consisting of the combination of four squares, two of them occupying diagonal corners, consisting of the representation of a bird, a surface of water, a setting sun, a butterfly, leaves, and branches, and two squares in the other diagonal corners, consisting of the representation of the branch of a wild-rose tree displaying an open bloom and leaves, all of said squares being surrounded by a border.

ALBERT LEISEL.
